UNITED STATES PATENT OFFICE.

ISADORE VANDERBECK, OF HUNTSVILLE, MISSOURI.

CHICKEN COOP.

Application filed October 29, 1921. Serial No. 511,339.

To all whom it may concern:

Be it known that ISADORE VANDERBECK is a citizen of the United States, residing at Huntsville, in the county of Randolph and 5 State of Missouri, has invented certain new and useful Improvements in a Chicken Coop, of which the following is a specification.

This invention relates to improvements in 10 coops for various fowls such as chickens, ducks and the like, and particularly to closures for such coops, the purpose being generally to provide a closure which may be partially removed or opened to permit the 15 placing or removal of certain of the fowls without danger of the others getting free.

A further object is to produce a closure which is provided with a fastening means which cannot be accidentally released to 20 permit the closure to be unintentionally opened to free the fowls within the coop.

A further object is to provide a closure, which while incapable of being accidentally released, may, by the simple application of 25 a tool such as a screw-driver, be quickly operated, and a further object is to provide a closure which is simple in structure and mode of operation, yet which securely maintains the coop in closed condition.

30 In the accompanying drawings,

Figure 1 is a top perspective view of the coop embodying my improved closure;

Figure 2 is a detail transverse sectional view through a portion of the coop having 35 the closure fastening device.

Figure 3 is a central longitudinal sectional view and,

Figure 4 is an end view of the coop.

Referring now more specifically to the 40 drawings by numerals of reference in which the characters refer to like parts throughout the several views, 2 designates generally the coop, which is usually rectangular in form and comprises side members 4, end members 6, a bottom 8 and top 9, each of which, except the bottom or floor member 8 is slatted as is common in this type of coop.

The present invention is directed toward 45 the closure and the means by which it is securely fastened in position and to this end, I have made provision for removing or partly removing by a longitudinal sliding movement, one of the slats which combine with the remainder to form the slatted top 55 member 9.

By preference, I provide the central slat 10 as forming the removable closure, and provide the top edge of the upper slats 12 of the end members 6 and the top edge of the upper slat 14 of a central partition 15 60 arranged transversely of the coop with rectangular recesses 16, all of which are arranged in longitudinal alinement, and receive the closure slat 10.

The slat 10 is secured in the recesses 16 of 65 the slats 12 of the end members 6, against upward movement by means of straps 18 extending across said recesses and secured by screws or other suitable fastening means 19. The slat is of less thickness than the depth 70 of the recess so that freedom of movement of the slat is permitted.

Centrally of its length, or, so arranged that it lies over the upper slat member 14 of partition 15, the slat closure 10 is provided with an aperture 22 which is adapted to receive the head 24 of a screw threaded locking bolt 26 threaded in a strap 28 which spans the recess 16 and is secured at its ends by screws 29 or the like, the free or upper 75 end being accessible for actuation by a screw driver or similar tool and provided with a kerf 30.

The screw threaded opening which receives the bolt 26 is countersunk to provide 85 a recess 32 which receives the head 24 of said bolt, so that when it is turned in a direction to retract the head from the aperture 22, it will be entirely clear from interference with the sliding movements of the said 90 slat 10.

It will therefor be clear that when the bolt 26 is in the position illustrated in Figure 2, it rests within the aperture 22 which prevents longitudinal movement of the closure slat, but when said bolt is retracted so that the head rests within the recess 32, the slat 10 is free to be slid longitudinally the desired distance to place or remove a fowl in or from the coop. 100

Having thus described my invention, what I claim as new and desire to protect by Letters Patent is:—

1. In a coop structure, a central transverse member having an upper closure slat 105 receiving recess, a closure slat longitudinally movable within said recess and provided with an aperture intermediate its ends, a strap secured to said central transverse member and spanning said recess, a 110

locking bolt perpendicular to said strap and movable into and out of said aperture in the closure slat, a head on said bolt and said strap being provided with a countersunk portion surrounding said bolt to receive the head thereof.

2. In a coop structure, end, bottom, side and top walls thereof, a central transverse member, said end, and transverse members being provided with longitudinally aligned recesses in the upper face of each, a closure slat longitudinally movable in said recesses and provided with an aperture adjacent the central transverse member when the slat

is in normally closed position, a strap spanning the recess in each of the end members, a strap secured to said central transverse member and spanning the recess therein, a threaded locking device mounted in and perpendicular to said strap and movable into and out of said aperture in the closure slat, and means whereby the locking device may be turned to project the same into or retract it from said closure slat aperture.

In testimony whereof I affix my signature.

ISADORE VANDERBECK.
